(57) **CLAIM**

The ornamental design for a distance measuring device, as shown and described.

DESCRIPTION

Fig. 1.1 is a top-right perspective view of a distance measuring device in accordance with our new design;
Fig. 1.2 is a top plan view thereof;
Fig. 1.3 is a left-side elevational view thereof;
Fig. 1.4 is a front elevational view thereof;
Fig. 1.5 is a bottom elevational view thereof;
Fig. 1.6 is a right-side elevational view thereof; and
Fig. 1.7 is a rear elevational view thereof.
The broken lines depict portions of the article that form no part of the claimed design.
